UNITED STATES PATENT OFFICE.

JOHN McFADDEN, OF SOUTH CHICAGO, ILLINOIS.

FOLDING SQUARE.

1,400,617.

Specification of Letters Patent. Patented Dec. 20, 1921.

Application filed May 25, 1920. Serial No. 384,066.

To all whom it may concern:

Be it known that I, JOHN McFADDEN, a citizen of the United States, residing at South Chicago, in the county of Cook and 5 State of Illinois, have invented new and useful Improvements in Folding Squares, of which the following is a specification.

This invention relates to a folding square and has for its primary object the construction of a square that may fold into a very compact formation and may be readily forced to its extended position and rigidly held at such position.

An object of the invention is the construction of a joint whereby the members may be folded into parallel relation or may extend at right angles to each other and rigidly lock in this position.

With these and other objects in view the 20 invention will be better understood from the following detailed description taken in connection with the accompanying drawing wherein:

Figure 1 is a side elevation of my invention when in extended position.

Fig. 2 is a view showing the square in folded position.

Fig. 3 is an edge elevation.

Fig. 4 is an enlarged sectional view.

30 Again referring to the drawing illustrating one construction of my invention the numeral 1 designates a main member, and the numeral 2 designates an auxiliary member. The main member 1 is formed with a slot 3 receiving the extension 4 that extends at right angles to the auxiliary member 2. A 35 rivet 5 pivotally connects the extension to member 1 in such a manner that the member 2 may fold into parallel relation with member 1, as illustrated in Fig. 2 of the drawing, or it may be extended at right angles to the member 2, as illustrated in Fig. 1 of the drawing.

This joint also assures accurate arrangement of the division marks 6 of the 45 member 2 with the division marks 7 of the member 1. For the purpose of accurately and rigidly connecting the members together I have illustrated the locking device 8 consisting of a tapering ferrule 9 engaging the 50 tapering holes 10 in the members and drawn into tight engagement therewith by the screw 11. From the foregoing description taken in connection with the accompanying drawing it will be apparent that I provide a 55 square that may be readily folded and may be just as readily extended and accurately locked in extended position so as to accomplish accurate measurements and to assure member 2 extending at right angles to member 1.

It is, of course, to be understood that the invention may be constructed in various other manners and the parts associated in different relations and, therefore, I do not 65 desire to be limited in any manner except as set forth in the claim hereunto appended.

Having thus described my invention what I claim is:

A folding square comprising a main member having a slot formed in one end portion, an auxiliary member having an extension at right angles thereto and arranged in said slot, said main member and extension provided with tapering holes adapted to be 70 placed in alinement when the members are disposed at right angles to each other, a pivot pin connecting the main member and extension, a frusto-conical ferrule in said tapering holes and provided with a threaded bore, 75 a cap screw threaded in said threaded bore to draw the ferrule in tight engagement with the holes, said main member recessed to receive the head of said ferrule.

In testimony whereof I affix my signature. 85
JOHN McFADDEN.
